(21) Appl. No.: **29/145,973**

The ornamental design for a portion of a computer display
with a computer icon graphic, as shown and described.

(22) Filed: **Jul. 31, 2001**

DESCRIPTION

(51) LOC (7) Cl. **14-02**

FIG. 1 is a front view of a portion of a computer display with
a computer icon graphic of the present invention;
FIG. 2 is a front view of a second embodiment thereof;
FIG. 3 is a front view of a third embodiment thereof; and,
FIG. 4 is a front view of a portion of a fourth embodiment
thereof.

(52) U.S. Cl. **D14/489**

The broken line drawing of a computer display with a
computer icon graphic is for illustrative purposes only and
forms no part of the claimed design.
